UNITED STATES PATENT OFFICE

CHARLES F. FREDE, OF ST. LOUIS, MISSOURI, AND EINAR G. HALLQUIST, OF EDWARDSVILLE, ILLINOIS, ASSIGNORS TO GENERAL STEEL CASTINGS CORPORATION, OF GRANITE CITY, ILLINOIS, A CORPORATION OF DELAWARE

LOCOMOTIVE STRUCTURE

Application filed June 16, 1930. Serial No. 461,417.

Our invention relates to railway steam locomotives and more particularly to the main steam cylinder structure and associated parts, including the adjacent framing of the locomotive, the boiler smoke-box support, the steam control valve chambers and the passages for the live steam and exhaust steam.

Our invention relates particularly to that type of locomotive in which the main steam cylinders are integral with the locomotive underframe or bed structure, such as disclosed in H. M. Pflager Patent 1,566,423, and it is one of the objects of our invention to provide a structure of this type which shall possess greater rigidity throughout the framing and between the framing and the cylinders.

An additional object of our invention is to provide steam exhaust and live steam passages integral with the framing, boiler support and steam valve chambers. We also desire to facilitate access to all the walls of the steam cylinders, valve chambers and steam passages so that the same may be inspected readily and any leaks therein may be repaired.

Another object of our invention is to protect the walls of the steam passages from undue exposure to air streams so as to maintain higher temperatures within the passages.

These and other detail objects are attained by the structures disclosed in the accompanying drawings, in which—

Figure 1 is a one-half top view of that portion of a locomotive bed and cylinder structure at the front of the drivers.

Figure 2 is a side elevation of the same.

Figure 3 is a bottom view of the same.

Figure 4 is a substantially horizontal section and view taken on the line 4—4 of Figure 5.

Figure 5 is a vertical transverse section taken approximately on the line 5—5 of Figure 4.

Figure 6 is a similar section taken on the line 6—6 of Figure 1.

Figure 7 is a vertical longitudinal section taken on the line 7—7 of Figure 5.

Figure 8 is a vertical section taken on the longitudinal center line of the structure.

Figure 9 is a vertical longitudinal section taken on the line 9—9 of Figure 1.

Figure 9a is a horizontal section taken on the line 9a—9a of Figure 9.

Figure 10 is a vertical transverse section 55 taken on the line 10—10 of Figure 2.

Figure 11 is a vertical transverse section taken on the line 11—11 of Figure 1.

Figure 12 illustrates a modified structure and is a horizontal section taken on the line 60 12—12 of Figure 13.

Figure 13 is a vertical transverse section through modified structure as taken on the line 13—13 of Figure 12.

Figure 14 is an end view of the cylinder 65 and saddle of the modified structure showing the bed in front of the saddle in section.

The preferred embodiment of our invention contemplates an integral casting structure forming an underframe and a cylinder 70 saddle in which the main longitudinal force-transmitting member of the under-frame is a box-shaped member extending substantially the full length of the underframe proper except for the portion immediately at 75 the rear of the cylinder saddle, which is arranged to accommodate the brake cylinders (not shown). This main member has a top wall 1, a bottom wall 2 and side walls 3. At the rear of the drivers, it will merge with 80 or be connected to the usual cradle structure. Walls 1, 2 and 3 will be provided with suitable openings at intervals to facilitate manufacture of the casting and to lighten the same, and the box-like member formed thereby will 85 be reinforced by suitable transverse ribs or partitions. It will be understood that the box-like member may vary in width and depth to suit different conditions at different points in its length.

Throughout a substantial portion of the length of the underframe we provide a supplementary side member 4, 4a on each side of the underframe. The portions of these side members abreast of the drivers are spaced 95 from the box-like member and include the pedestal jaws 35 and mount the usual equalizers, brake hangers, valve gear brackets and other moving parts (not shown). For reasons which will be stated below, this entire 100

supplementary side member is not extended in a continuous straight line past the cylinder and boiler saddle structure. The side walls 3 of the box-like member form the inner walls of the side members 4 and 4a in front of the cylinders.

It will also be understood that the main longitudinal force transmitting member may comprise two spaced members having vertical webs or a single member having a vertical web and laterally extending flanges.

The main steam cylinders are indicated at 5 and 6 and each is provided with a corresponding steam supply valve, the chamber for which is shown at 7 and 8, respectively. These cylinders and valve chambers are supported from the main member by a substantially box-like saddle structure comprising front and rear walls 9 and 10, respectively, and horizontal top and bottom webs 11 and 12, respectively, which are substantially in line with the box walls 1 and 2. Walls 9 and 10 extend upwardly above the level of the center member and above the supply valve chambers and are connected by upright walls 14, all of these walls forming the sides of a box which has an arcuate top plate 15 on which the smoke-box of the boiler rests. A depression 16 on each side of the saddle and an elevated flange 16a cooperate to form a horizontal shelf which is provided with an opening to the live steam passageway 17 which leads direct to the adjacent steam valve chamber. The inlet end of this passageway is circular in cross section and shelf 16—16a, surrounding the inlet end, forms a mounting for a pipe fitting.

Exhaust steam passages 18 extend inwardly and upwardly from the ends of the valve chamber and converge towards each other, their walls merging near the center of the structure to form a support for the central portion of the top plate on which the usual exhaust nozzle will be mounted.

The arrangement of the steam passageways as described and illustrated provides substantial spaces S between each live steam passageway and the adjacent exhaust steam passageways whereby the side walls of these passageways are accessible for inspection and for any necessary repairs. These spaces also provide access to the valve chamber inner side which faces towards the center line of the locomotive. In order to permit similar access to the corresponding side of the main steam cylinder and at the same time permit access to the bottom walls of the steam passageways 17 and 18, we provide substantial openings A and B in the horizontal webs 11 and 12 which extend outwardly from the main underframe member 1—2—3.

A portion of the top wall 1 of the main member is inclined upwardly, as indicated at 20, abreast of the cylinders. This inclined portion 20 is reinforced by a suitable flange 21

projecting downwardly therefrom. A similar reinforcing flange 22 substantially surrounds the opening A in web 11 and a corresponding flange 23 is provided around the opening B in the web 12.

Restricted parts of web 11 and wall 1 form the bottom of the exhaust steam passages 18 adjacent to their convergence with each other.

Similarly, walls 9 and 10 are provided with openings C to facilitate access to the inner wall of the cylinder.

The openings S, A and B are large enough for a man to get down into the casting behind the valve chamber and steam cylinder and near the bottom wall of the live steam passage for closing any leaks or otherwise working on the adjacent walls of the structure. With such work in mind, it will be readily understood that the narrowing of the steam passageways 17 and 18 is of substantial advantage because it makes possible larger openings. To the same end, we have terminated each supplementary side member 4, 4a near the ends of the cylinder and have provided arcuate connections 24 between the supplementary side members and the side of the cylinder whereby the cylinder walls form, in effect, a continuation of the supplementary side member through the saddle portion without unduly restricting the space behind the cylinders as would be done if the vertical walls of members 4, 4a continued through the saddle structure. Horizontal webs 11 and 12 contribute to this feature of our construction.

Similar openings D, E and F are provided in the front wall 9 to facilitate molding and inspection. Openings G and H are provided in the rear wall 10 for the same purposes. Openings J and K are provided in the top plate 15 and openings L and M are provided in the bottom wall 2 of the main member, all these openings being provided for molding and inspection purposes.

The metal surrounding openings D, E, F, G, H, J, K and L is finished by counter-boring or other machining and cover plates P are applied thereto, preferably by welding, after the bed is finished. This prevents access of cold air to the walls of the steam passageways and to the inner sides of the cylinders and steam valve chambers and reduces the amount of condensation which would otherwise occur in the steam filled compartments of the device. The openings S are closed by means of the usual jacket around the cylinder and steam chest.

Summarizing the features described above, it will be seen that we have provided a locomotive bed having a main box-like backbone member extending from the front of the bed through the cylinder and smoke-box saddle portion of the locomotive to the rear wall of the latter and have provided, in an integral structure, cylinders, valve chambers, live

and exhaust steam passageways, all spaced under carrying elements connecting said support and cylinder element.

2. A device as described in claim 1 in which all of the elements are united in an integral structure free from bolts or rivets or like separately formed securing means. 70

3. In a locomotive structure, a boiler smoke-box support, a main steam cylinder element, a steam supply chamber element above said cylinder element, said cylinder and chamber elements being spaced from said smoke-box support so as to permit entry of a workman between them from below, and cylinder and steam chamber carrying elements connecting the latter with said support. 75

4. A device as described in claim 3 in which all of the elements are united in an integral structure free from bolts or rivets or like separately formed securing means. 80

5. In a locomotive structure, a boiler smoke-box support, a main steam cylinder element, and steam passage elements connecting said support and said cylinder element, and said support and cylinder element being spaced from each other and said steam passage elements being spaced from each other so as to permit the entry of a workman between them from below. 85 90

6. A device as described in claim 5 in which all of the elements are united in an integral structure free from bolts or rivets or like separately formed securing means. 95

7. In a locomotive structure, a boiler smoke-box support, a main steam cylinder element, exhaust steam passage elements extending from the ends of said cylinder element to said support, and a live steam passage element extending similarly intermediate said exhaust steam passage elements, said support and said cylinder element being spaced from each other and said steam passage elements being spaced from each other so as to permit entry of a workman between them from below. 100 105

8. A device as described in claim 7 in which all of the elements are united in an integral structure free from bolts or rivets or like separately formed securing means. 110

9. In a locomotive structure, a boiler smoke-box support, a main steam cylinder element, a steam supply chamber element above said cylinder element, and steam passage elements connecting said support and said cylinder and chamber elements, said support and said cylinder and chamber elements being spaced from each other and said passage elements being spaced from each other so as to permit the entry of a workman between them from below. 115 120 125

10. A device as described in claim 9 in which all of the elements are united in an integral structure free from bolts or rivets or like separately formed securing means. 130

11. In a locomotive structure, a boiler smoke-box support, a main steam cylinder ele- 135

5 the sides of the main member we have provided additional elements cooperating with the main member to form supplementary box-like sections. Abreast of the cylinders and valve chambers, the outer wall of each 10 side member is merged with the adjacent portion of the cylinder wall whereby the latter forms a part of a continuous longitudinal force-transmitting element and greater space is afforded between the main member 15 and the cylinder.

We have avoided undue condensation of steam in the cylinders and steam passages by excluding air from a substantial portion of the steam retaining walls. This latter feature is augmented in the preferred structure by forming the live steam passages integral with the saddle and valve chamber and by extending the inlet end inside of the smoke box. 20

25 Nearly all of the desirable features of our structure are retained, however, in the modified construction illustrated in Figures 12 to 14 which illustrate a structure having outside live steam passages 25 provided with flanges 26 for mounting pipe fittings in the usual manner. This structure provides an increased space Q between the valve chamber 27 and the boiler saddle wall 28 and facilitates access to the outer surface of the inner walls of the valve chamber and the exhaust steam passages 29. Aside from this large upper opening, access to the outer surface of the inner walls of the main steam cylinders 30 and to the side walls 31 of the central 35 member is not affected. In this structure the width of the boiler support member 32 is substantially less than the corresponding member shown in the preferred structure and, obviously, the molding of this portion 40 of the saddle structure is simplified by the elimination of the live steam inlet portion.

While the preferred embodiment of our invention is in the form of a one-piece casting, many of the described features are not limited to this embodiment and the same and their attending advantages may be involved in a structure formed by welding separately formed members into an integral whole, and some of the features may be embodied in a structure assembled in the usual manner by means of bolts and rivets. We contemplate the exclusive use of these and other modifications of our design which come within the 55 scope of our claims. 60

We claim:

1. In a locomotive device, a boiler smoke-box support, a main steam cylinder element spaced therefrom so as to permit entry of a 65 workman between them from below, and cyl-

ment; a steam control chamber element above said cylinder element, exhaust steam passage elements extending between the ends of said cylinder and chamber elements and said support, and a live steam passage element extending similarly intermediate said exhaust steam passage elements, and said support element and said cylinder and chamber elements being spaced from each other and 10 said steam passage elements being spaced from each other so as to permit entry of a workman between them.

12. A device as described in claim 11 in which all of the elements are united in an 15 integral structure free from bolts or rivets or like separately formed securing means.

13. In a locomotive structure, a boiler smoke-box saddle, main steam cylinders on opposite sides of said saddle and spaced therefrom so as to permit entry of a workman between said saddle and each of said cylinders, and live and exhaust steam passages extending from each of said cylinders to said saddle and similarly spaced from each other, all 20 of said parts being integral with each other.

14. In an integral structure for locomotives, a longitudinal force-transmitting member, a main steam cylinder, a steam supply chamber, a boiler support, and a live steam 25 passageway extending from said chamber intermediate its ends to said support.

15. In an integral structure for locomotives, a longitudinal force-transmitting member, a main steam cylinder, a steam supply 30 chamber, a boiler support, exhaust steam passageways between said chamber and cylinder and said support, and a live steam passageway between said chamber and said support intermediate said exhaust steam passageways.

16. An integral locomotive bed structure including a main frame member, a steam supply chamber, a boiler support, and a live steam passageway extending from said supply chamber intermediate its ends to said 40 boiler support.

17. In a locomotive structure, a main longitudinal force-transmitting member, a main steam cylinder spaced therefrom, a supplementary longitudinal force-transmitting member substantially paralleling said main member and spaced outwardly therefrom and terminating adjacent the end of said cylinder but connected thereto, said cylinder thereby 50 constituting a continuation of said supplementary member and receiving the longitudinal forces transmitted thereto.

18. In a locomotive structure, a steam supply chamber, a smoke-box support having a 60 top plate curved to engage a cylindrical smoke-box, and a live steam passage having an inlet opening through said plate and an outlet opening to said chamber, said inlet opening being surrounded by cooperating 75 elements constituting a depression in said

plate and an adjacent flange forming a horizontal shelf for supporting a steam pipe.

19. In a locomotive structure, a main force-transmitting member of box-shaped cross section, a main steam cylinder spaced from the side of said member, the top wall of said member being projected beyond its side wall and towards said cylinder and a portion of said side wall forming a wall of a steam passage and being curved upwardly and inwardly from the side of said member. 75

20. In a locomotive structure, a main force-transmitting member, a steam cylinder spaced therefrom, a valve chamber, a smoke-box support having a top plate, an exhaust steam passage extending from said chamber through said top plate, and a substantially horizontal web connecting said cylinder and member, a portion of said web forming a portion of the bottom wall of said passage, there being an opening in said web at the side of said passage to provide access to the portion of the wall of said cylinder below said opening. 80

21. In a locomotive structure, a smoke-box support having a top plate, a steam cylinder spaced from the side of said support, a valve chamber above said cylinder, an exhaust steam passage extending transversely and diagonally inwardly and upwardly from each end of said chamber and merging with an opening in said top plate, a live steam passage extending transversely and upwardly from the central portion of said chamber to an opening in said top plate, there being an open space on each side of said live steam passage between the latter and the corresponding exhaust steam passage for access to the sides and bottom of said live steam passage. 95

22. In a locomotive structure, a smoke-box support having a top plate, a steam cylinder spaced from the side of said support, a valve chamber above said cylinder, an exhaust steam passage extending transversely and diagonally inwardly and upwardly from each end of said chamber and merging with an opening in said top plate, a live steam passage extending transversely and upwardly from the central portion of said chamber to an opening in said top plate, there being an open space on each side of said live steam passage between the latter and the corresponding exhaust steam passage for access to the sides and bottom of said live steam passage, and a substantially horizontal web extending inwardly from said cylinder and below said steam passages, there being an opening in said web adjacent said cylinder for access to the inner wall of said cylinder and to the bottom of said live steam passage. 110

23. In a locomotive underframe structure, a longitudinal force-transmitting member, a steam cylinder spaced from the side of said member, a valve chamber above said cylinder, 115

- 5 a smoke-box support above said member having a top plate, an exhaust steam passage extending diagonally inwardly and upwardly from each end portion of said cylinder and chamber to the opening in said top plate, a live steam passage extending transversely inwardly and upwardly from the central portion of said chamber to another opening in said top plate, there being spaces 10 between said live steam passage and said exhaust steam passages, and a plurality of substantially horizontal web plates connecting said member and said cylinder, each web plate having an opening adjacent said cylinder, said spaces and said openings and said web plates providing access by a workman to the inner wall of said cylinder and to the side and lower walls of said live steam passage.
- 15 24. In a locomotive underframe structure, a central longitudinal force-transmitting member, a longitudinal force-transmitting member spaced from said central member, a main steam cylinder spaced from said central member, an arcuate vertical web connecting the end of said element and the end of said cylinder, and a horizontal web connecting said central member and the side of said cylinder.
- 20 25. In a locomotive underframe structure, a central box-shaped longitudinal force-transmitting member, a force-transmitting element on each side of said member each having a vertical wall spaced from the adjacent side wall of said member, and a main steam cylinder located at the outer side of each of said elements, each of said elements ending in the rear of said cylinder and the end of each of said elements being connected to the end of the corresponding cylinder.
- 25 26. In a locomotive underframe structure, a central longitudinal force-transmitting member, a main steam cylinder spaced outwardly from said member, additional force-transmitting elements extending forwardly and rearwardly from the ends of said cylinder and positioned outwardly of said member, the ends of said cylinder being connected to the adjacent ends of said elements.
- 30 27. In a locomotive cylinder and underframe structure, a central longitudinally disposed member, a steam cylinder on each side of said member and spaced therefrom, a valve chamber above each cylinder, a smoke-box support located above said member between said cylinders and having front and rear walls extending from the top of said support to the bottom of said member and extending transversely between and connected to said cylinders and valve chambers, a pair of vertically spaced substantially horizontal web plates connected to and extending between said cylinders and member, an opening in each of said plates adjacent to the cylinder wall, an open-
- 35 ing in said front and rear walls adjacent the wall of each cylinder and between said horizontal web plates, a longitudinal member spaced from said central member and in front of said cylinders and connected to the front end of said cylinders at a point spaced from said front wall, a longitudinal member spaced from said central member and in the rear of said cylinders and connected to the rear end of said cylinders at a point spaced from said rear wall, the openings in said horizontal web plates and front and rear walls permitting inspection of and access to the portion of the cylinder walls adjacent said openings.
- 40 28. In a locomotive structure, a pair of transversely spaced steam cylinders, a pair of vertically spaced substantially horizontal web plates connected to and extending between said cylinders, a pair of longitudinally spaced substantially vertical transverse members connected to and extending between said cylinders, all of said members being connected to said cylinders at points intermediate the ends of said cylinders, a longitudinally disposed element extending forward of each of said cylinders and having a vertical wall connected to the front end portion of said cylinders, a longitudinally disposed element extending rearward of each of said cylinders and having a vertical wall connected to the rear end portion of said cylinders, there being openings in said walls and members to permit inspection of and access to the sides of said cylinders which face towards the center line of the locomotive.
- 45 29. In a locomotive cylinder structure, a pair of transversely spaced steam cylinders, a valve chamber above each of said cylinders, a smoke-box support located between said cylinders and having a top member, steam passages extending from said chamber to said member, a substantially horizontal web connected to and extending between said cylinders, there being at least one opening in said web intermediate its ends for inspection of the interior of said structure and to suit moulding conditions, and a plate for closing said opening so as to prevent circulation of air inside of said structure and thereby reduce condensation in said passages.
- 50 30. In a locomotive cylinder structure, a pair of transversely spaced steam cylinders, a valve chamber above each cylinder, a substantially box-like structure connected to and extending between said cylinders and chambers and having top and bottom and front and rear walls, steam passages extending from said chambers to said top wall, there being at least one opening in each of said walls, intermediate their ends, for inspection of and access to the interior of said structure and the walls of said passages, and plates for closing said openings so as to prevent circula-
- 55 60 65 70 75 80 85 90 95 100 105 110 115 120 125 130

tion of air inside of said structure whereby condensation in said passages is reduced.

31. In a locomotive structure, a main longitudinal force-transmitting member of box-like cross section, a main steam cylinder spaced from the side of said member sufficiently to permit a workman to enter between them and have access to the entire inner wall of said cylinder and other adjacent parts for the purpose of inspection and repair, and elements integrally uniting said member and cylinder.

32. In a locomotive structure, a main longitudinal force-transmitting member, a main steam cylinder spaced outwardly therefrom, supplementary longitudinal force-transmitting members spaced outwardly from said main member and substantially paralleling the same and terminating in front of and behind said cylinder respectively, said supplementary members being connected to the adjacent ends of said cylinders whereby said cylinder constitutes a force-transmitting element between said supplementary members.

33. In a locomotive, an underframe including a main body member having substantially horizontal top and bottom webs, and a cylinder saddle structure including a main force-transmitting member, main steam cylinders spaced on each side of said force-transmitting member, and substantially horizontal web plates extending between said cylinders and in line with the top and bottom webs of said main body member.

35. In testimony whereof we hereunto affix our signatures this 13th day of June, 1930.

CHARLES F. FREDE.
